UNITED STATES PATENT OFFICE.

JAMES T. MCCOLLUM, OF DARDANELLE, ARKANSAS.

MAIL-CARRYING DEVICE.

1,104,916.

Specification of Letters Patent.

Patented July 28, 1914.

Application filed May 9, 1914. Serial No. 837,532.

To all whom it may concern:

Be it known that I, JAMES T. MCCOLLUM, a citizen of the United States, residing at Dardanelle, in the county of Yell and State 5 of Arkansas, have invented certain new and useful Improvements in Mail-Carrying Devices, of which the following is a specification, reference being had to the accompanying drawings.

10 This invention relates to certain improvements in mail carrying devices and has relation more particularly to a device of this general character especially designed and adapted for use in such localities wherein 15 the rural service is provided; and the object of the invention is to provide a device of this general character having novel and improved means whereby the carrier proper may be caused to travel with convenience and facility toward or from the house and a receiving 20 locality, preferably at the roadside.

The invention consists in the details of construction and in the combination and arrangement of the several parts of my improved mail carrying device whereby certain 25 important advantages are attained and the device is rendered simpler, less expensive and otherwise more convenient and advantageous for use, all as will be hereinafter more 30 fully set forth.

The novel features of the invention will be carefully defined in the appended claims.

In order that my invention may be better understood, I will now proceed to describe the same with reference to the accompanying drawings, wherein—

Figure 1 is a diagrammatic view partly in elevation and partly in section of a mail-carrying device constructed in accordance with 40 an embodiment of my invention; Fig. 2 is an enlarged front elevational view of the operating mechanism for the device as herein disclosed; Fig. 3 is a sectional view taken substantially on the line 3—3 of Fig. 2; Fig. 4 is a sectional view taken substantially on the line 4—4 of Fig. 2; Fig. 5 is a sectional view taken substantially on the same line as the section of Fig. 4, but in a reverse direction; Fig. 6 is a front elevational view exterior of 45 a building with which my device co-operates, certain of the parts being in section; and Fig. 7 is a fragmentary elevational view 50 illustrating a somewhat modified form of invention.

55 As disclosed in the accompanying drawings, 1—1 denote vertically disposed parallel

bars maintained in operative position upon the wall of a building structure through the medium of the supporting brackets 2, such brackets being of such dimensions as the 60 necessities of practice may require. Loosely directed through the bars 1 are the horizontally disposed shafts 3—3 disposed in parallelism and maintained against endwise movement through the medium of the collars 4 65 adapted to contact with the bars 1 in a manner which is believed to be self-evident. In practice, it is preferred that the bars 1 be positioned in such close proximity to an entry opening in the house as to permit adjacent end portions of the shafts 3 to intersect the vertical plane occupied by such opening. I also find it desirable to have the house provided with an independent entry opening 5 for the mail carrier 6, to be hereinafter more 70 particularly set forth and through which such carrier is adapted to pass into the house. This opening 5 is adapted to be normally closed by the inwardly moving doors 7; herein disclosed as under control of the springs 80 8 for maintaining such doors normally in closed position. When my improved device is employed in connection with such an independent or separate entry opening 5, it will be readily perceived that the bars 1 are 85 so positioned relative thereto as to have the lower shaft 3 substantially flush with the upper wall of the opening 5. The projected portions of the shafts 3 have suitably affixed thereto the spools or drums 9, to which are 90 connected the opposite extremities of a flexible member or cord 10, such flexible member or cord being also directed around an idle pulley or spool 11 suitably mounted upon a post 12 or other support properly 95 positioned at the roadside and to the lower reach or stretch of the flexible member or cord 10 is suitably secured the carrier or box 6. While I do not wish to limit myself as to any particular form or style of carrier or box 100 6, I wish to state that I prefer to have the same formed of as light material as will best serve the purpose. As is thought to be obvious, the lower stretch of the flexible member or cord 10 will pass through the 105 upper portion of the opening 5 while the upper stretch of such flexible member or cord will be directed through a restricted opening 14 produced in the wall at the requisite point above the opening 5.

Rotatably supported by the bars 1 is the intermediate horizontal shaft 15, one ex-

tremity of which having affixed thereto an enlarged gear wheel 16 adapted to mesh with the smaller gear wheels 17 affixed to the shafts 3, whereby it will be readily perceived that upon suitable rotation of the intermediate shaft 15, the shafts 3 will be so rotated as to cause the flexible member or cord 10 to wind upon one spool and unwind from the other. The opposite extremity of the intermediate shaft 15 is provided with a small gear wheel 18 adapted to mesh with a large gear wheel 19 mounted on the short shaft 20 rotatably supported by one of the cross bars 1 and auxiliary bracket or support 21, such shaft 20 being operatively engaged at one extremity by the crank member 22 whereby it will be readily perceived that a convenient means is afforded to impart the requisite rotation to the shafts 3 in order to cause the carrier or box 6 to move toward the roadside or vice versa.

I find in practice that it is extremely desirable to have the return travel of the carrier or box 6 effected in an automatic manner and, as herein disclosed, I accomplish this purpose through the medium of the spring motor 23 operatively connected with the shaft 20, the spring of such motor being wound or spaced under tension when the shaft 20 is manually operated in order to cause the carrier or box 6 to travel away from the building. Rotation of the shaft 20 under the influence of the motor 23 is prevented through the medium of the dog 24 coacting with such motor in a conventional manner and, as herein disclosed, such dog has engaged therewith a flexible member or cord 25 which is directed exteriorly of the building and terminates in close proximity to the idle spool or pulley 11 so that the postman, after he has delivered his mail within the box or carrier 6, may release such dog so that the box or carrier 6 under the influence of the motor 23 will return within the building.

From the foregoing description, it is thought to be obvious that a mail carrying device constructed in accordance with my invention is of an extremely simple and comparatively inexpensive nature and is particularly well adapted for use by reason of the convenience and facility with which it may be assembled and by reason of the effectiveness with which it performs its functions, and it will also be obvious that my invention is susceptible of some change and modification without material departure from the principles and spirit thereof and for this

reason I do not wish to be understood as limiting myself to the precise arrangement and formation of the several parts herein shown in carrying out my invention in practice.

As disclosed in Fig. 7, is illustrated an embodiment of my invention wherein the carrier 6' is operatively supported by a track 65 26 which arrangement is especially desirable when the carrier has to travel a great distance. The flexible member or cord 10' is operated in the identical manner as has been set forth relative to the flexible member or 70 cord 10.

I claim:

1. A device of the character described comprising a plurality of drums, a flexible member having its extremities connected to certain of such drums and being directed around the remainder, a carrier operatively connected with such flexible member, manual means for positively driving the drums with which the extremities of the flexible member are connected in one direction, and automatic means for imparting movement to such drums in an opposite direction. 80

2. A device of the character described comprising a plurality of drums, a flexible member having its extremities connected to certain of such drums and being directed around the remainder, a carrier operatively connected with such flexible member, manual means for positively driving the drums with which the extremities of the flexible member are connected in one direction, and automatic means for imparting movement to such drums in an opposite direction, such automatic means being under control of the manually operated means. 95

3. A device of the character described comprising a plurality of drums, a flexible member having its extremities connected to certain of such drums and being directed around the remainder, a carrier operatively connected with such flexible member, manual means for positively driving the drums with which the extremities of the flexible member are connected in one direction, automatic means for imparting movement to such drums in an opposite direction, and releasable means for controlling the operation of said automatic means. 105

In testimony whereof I hereunto affix my 110 signature in the presence of two witnesses.

JAMES T. McCOLLUM.
